UNITED STATES PATENT OFFICE.

JOHN CALLAHAN, OF LYNN, MASSACHUSETTS.

PRESSER-FOOT.

1,154,373.

Specification of Letters Patent. Patented Sept. 21, 1915.

Original application filed December 29, 1903, Serial No. 186,958. Divided and this application filed May 8, 1905. Serial No. 259,283.

To all whom it may concern:

Be it known that I, JOHN CALLAHAN, a citizen of the United States, and a resident of Lynn, in the county of Essex and State 5 of Massachusetts, have invented certain new and useful Improvements in Presser-Feet, of which the following is a specification.

The present invention comprises a presser adapted for use in connection with sewing- 10 machines, etc., and operating mechanism therefor, the object of the invention being to provide an improved form of presser and operating mechanism having provisions by which the presser and operating mechanism 15 may be manually disconnected at the conclusion of an operation so that the presser may be separated from the work-support to remove a completed piece of work and insert a new piece. This invention covers the 20 presser illustrated and described in the patent granted to me May 30, 1905, numbered 791,005, and is a division of the application on which said patent was granted.

Of the accompanying drawings,—Figure 25 1 represents an end elevation of a sewing-machine having my improved presser and operating mechanism applied thereto. Fig. 2 represents a side elevation of the same. Fig. 3 represents a detail elevation of the 30 mechanism for operating the presser.

The same reference characters indicate the same parts in all the figures, and are the same as those used in the patent referred to.

The presser-foot is represented by the number 59 and is carried by a bar 60 movable longitudinally in bearings on the machine-frame, being operated from a cam 64 on the main shaft 260 of the machine through an arm 642, link 63 and lever 61 connected to 40 the bar 60. Power is furnished to the shaft 260 by means of a pulley 27 adapted to receive a belt, although obviously any other desired means for rotating the shaft might be employed. The lever 61 is pivoted at 62 45 to the machine-frame and securely fastened in any desired way to the presser-bar 60. If desired, a portion of the lever may be made of yielding material in order that the presser-foot may have a yielding action upon the 50 work.

Connection between the link 63 and lever 61 is made by means of a pin 93 occupying a recess or notch 94. In the form shown the pin mounted on the link and the notch 55 or recess is formed in the rear end of the

lever, although obviously the relation of the pin and notch might be reversed. A spring 95 connected both to the link and lever is provided and arranged so as normally to tend to hold the pin at the bottom or end 60 of the notch. Driving connection between cam 64 and link 63 is made by means of a rocker-arm 642 pivoted at 643 to the machine-frame and at 644 to the link. A stud 641 on the rocker-arm projects into a cam-groove 640 in the face of the cam. It will therefore be seen that as the shaft 260 and cam 64 rotate, a portion of the cam-groove being eccentric, the link is reciprocated vertically and as it is so reciprocated, the projection 93 engages first one side and then the other of the recess 94 to oscillate the lever 61 and raise and lower the presser-foot for permitting feed of the work and clamping it between the steps of the feed. Ordinarily 70 with a presser of this character, the foot will be pressed down upon the work at the end of a complete operation and in order to remove the finished work and substitute a new piece, it is necessary to separate the foot 80 from the work-support, and in order to permit such separation, means under the control of the operator is provided for disconnecting the presser from its operating mechanism. This means consists of a lever 96 85 pivoted at 97 to the machine-frame and having one arm extended adjacent the end of link 63 so that when the lever is rotated this end will engage the link and move it away from the lever 61 against the tension of 90 spring 95 to separate pin 93 from the slot 94. When this has been done the lever 61 and presser will be free to be moved manually and the latter can then be separated from the work-support a sufficient distance 95 to release the work. The link on being released is drawn toward the lever 61 by spring 95 but as the notch is then out of line with pin 93 the latter will rest against the end 611 of the lever above the notch. With 100 the construction shown the link will be raised to its highest position when this manual operation of the presser-foot is effected and consequently pin 93 will be above the notch 94 and on starting the machine again 105 the link will be lowered and the pin as soon as it reaches the level of the notch will be drawn into the latter by the force of the spring, thus automatically reconnecting the presser with its operating mechanism with- 110

out attention on the part of the operator. It is obvious that the arrangement of the parts may be reversed without affecting the principle or manner of operation of the invention.

5 Preferably the lever 96 will be provided with a projecting guide 961 arranged to extend over the side of the link 63 opposite to that on which lever 61 is situated, thus 10 guiding the link and retaining it in proper position for the pin carried by it to engage in the recess.

Although I have shown my improved 15 presser and operating mechanism therefor in connection with a sewing-machine, it is obvious that the presser is not limited to use in such a relation since it can also be as well used in any other machine which 20 performs a series of operations on work requiring the work to be intermittently held and released between operations.

I claim:—

1. The combination of a work-support, stitching mechanism, presser-operating 25 mechanism to force a presser against the work-support and work held thereon, a presser disconnectible from said operating mechanism through the agency of the operator, and provisions for automatically re- 30 connecting said presser with its operating mechanism by the movement of the latter.

2. The combination of a work-support, a presser, operating mechanism therefor including a lever and a reciprocating link having 35 a disconnectible pin and slot engagement, yielding means tending to hold said link and lever in operative connection, means under the control of the operator for disconnecting the same, and provisions for 40 retaining the same out of operative connection, said provisions being constructed and arranged to permit automatic re-connection thereof when the operating mechanism is in a predetermined position relative to the 45 presser.

3. The combination of a work-support, a presser, and operating mechanism for the presser comprising in part a reciprocable member, mechanism for reciprocating such 50 member, and a member connected to the presser, one of said members having a recess and the other a projection arranged to enter the recess and engage alternately the opposite sides thereof, such sides being 55 abrupt to the line of motion of the projection, whereby driving movement is imparted from one of said members to the other.

4. The combination of a work-support, a presser, a bar carrying the presser, a member 60 connected to the bar, operating mechanism for the bar and presser comprising in part a reciprocable member, one of said

members having a recess and the other a projection arranged to enter the recess and engage the opposite sides thereof alternately and in a manner such as to cause motion, and means actuatable by the operator for separating said projection from the recess to disconnect the presser bar from the operating mechanism.

5. The combination of a work-support, a presser, and operating mechanism therefor, comprising in part a reciprocating member, an intermediate member suitably connected with the presser; one of said members having a projection and the other having a notch adapted to receive said projection, and also having surfaces extending from said notch adapted to engage said projection and 70 permit the same to slide thereon when it is out of the notch; and yielding means drawing said members together.

6. The combination of a work-support, a presser, and operating mechanism for the 85 presser comprising in part a member connected to the presser, and a reciprocable member, one of said members having a slot and the other a projection arranged to enter the recess and engage the sides thereof, 90 and an arm operable by the machine operator to engage said reciprocable member and move the same away from the other member, whereby the projection is removed to a location outside of the slot.

7. In combination, a presser, a work-support, mechanism for operating said presser toward and holding it adjacent to said work-support, an actuator for disengaging the presser from said operating mechanism 100 while held adjacent the work-support, whereby the presser may be moved away from the work-support while the operating mechanism remains stationary, and yieldable connecting means tending to bring and 105 retain in connection the operating mechanism and presser operative to cause an automatic connection thereof upon further movement of the operating mechanism.

8. A presser mechanism comprising a 110 presser foot, a member connected with said foot and having a notch, an actuating member having a pin normally contained in said notch and engageable with the opposite sides of the notch during movements in opposite 115 directions respectively, and manually operated means for displacing said pin from said notch, whereby to disconnect the presser foot from the actuating member.

In testimony whereof I have affixed my 120 signature, in presence of two witnesses.

JOHN CALLAHAN.
